CLAIM

The ornamental design for a co-axial cable connector, as shown and described.

DESCRIPTION

FIG. 1 is a perspective view of a co-axial cable connector showing my new design;

FIG. 2 is a side elevational view thereof, the other side being a mirror image;

FIG. 3 is a top view, the bottom view being a mirror image thereof;

FIG. 4 is an end view thereof; and,

FIG. 5 is an opposite end view thereof.

The broken lines depict environmental structure and form no part of the claimed design.

The knurling in FIGS. 1-3 is depicted as hidden lines and is environmental in nature.
